(57) **CLAIM**

The ornamental design for an exercise device, as shown and described.

DESCRIPTION

FIG. 1 is a front isometric view of an exercise device in accordance with a first embodiment of the present invention; FIG. 2 is a top plan view of the exercise device illustrated in FIG. 1;

FIG. 3 is a front elevation view of the exercise device illustrated in FIG. 1, wherein the rear elevation view is the same;

FIG. 4 is a first side elevation view of the exercise device illustrated in FIG. 1, wherein the second side elevation view is the same;

FIG. 5 is a bottom plan view of the exercise device illustrated in FIG. 1;

FIG. 6 is a front isometric view of an exercise device in accordance with a second embodiment of the present invention;

FIG. 7 is a top plan view of the exercise device illustrated in FIG. 6;

FIG. 8 is a front elevation view of the exercise device illustrated in FIG. 6, wherein the rear elevation view is the same;

FIG. 9 is a first side elevation view of the exercise device illustrated in FIG. 6, wherein the second side elevation view is the same;

FIG. 10 is a bottom plan view of the exercise device illustrated in FIG. 6;

FIG. 11 is a front isometric view of an exercise device in accordance with a third embodiment of the present invention;

FIG. 12 is a top plan view of the exercise device illustrated in FIG. 11;

FIG. 13 is a front elevation view of the exercise device illustrated in FIG. 11, wherein the rear elevation view is the same;

(Continued)

FIG. 14 is a first side elevation view of the exercise device illustrated in FIG. 11, wherein the second side elevation view is the same; and,

FIG. 15 is a bottom plan view of the exercise device illustrated in FIG. 11.
